CLAIM

The ornamental design for a wire gripper, as shown and described.

DESCRIPTION

FIG. 1 is a front view of our design for a wire gripper; FIG. 2 is a rear view thereof; FIG. 3 is a top view thereof; FIG. 4 is a bottom view thereof; FIG. 5 is a right side view thereof; FIG. 6 is a left side view thereof; FIG. 7 is a front view showing a state of use thereof; FIG. 8 is a rear view showing a state of use thereof; FIG. 9 is right side view showing a state of use thereof; FIG. 10 is a front, right side perspective view thereof; and, FIG. 11 is a rear, right side perspective view thereof. The broken lines throughout the figures depict portions of the wire gripper that form no part of the claimed design. Additional broken lines showing hands in FIGS. 7-8 and a wire in FIG. 9 are environment of the wire gripper that form no part of the claimed design.
